UNITED STATES PATENT OFFICE.

IRA B. WHITE, OF FORT WORTH, TEXAS.

GRAIN-CAR-DOOR OPENER.

1,418,343.

Specification of Letters Patent. Patented June 6, 1922.

Application filed June 11, 1921. Serial No. 476,661.

To all whom it may concern:

Be it known that I, IRA B. WHITE, a citizen of the United States, residing at Fort Worth, in the county of Tarrant and State 5 of Texas, have invented certain new and useful Improvements in Grain-Car-Door Openers, of which the following is a specification, reference being had therein to the accompanying drawings.

10 This invention relates to a grain car door opener, and the object of the invention is the provision of simple and efficient means that can be readily applied for the opening of a grain car door that preferably is constructed of parts which are nailed or otherwise fastened to the frame of the car.

15 With this and other objects in view, my invention comprises certain novel combinations, constructions and arrangements of 20 parts as will be hereinafter described, illustrated in the accompanying drawings, and more particularly pointed out in the appended claims.

In the drawings:

25 Figure 1 is a view, in side elevation, of a device constructed in accordance with the present invention.

Figure 2 is a view, in side elevation, of the device shown as it appears in actual use.

30 Figure 3 is a view, taken on line 3—3, Fig. 2, and looking in the direction of the arrows.

Figure 4 is an enlarged, perspective view 35 of the primary jaw device.

Figure 5 is a sectional view, taken on line 5—5, Fig. 1, and looking in the direction of the arrows.

Figure 6 is an enlarged, perspective view 40 of the auxiliary jaw device, partly shown in section.

Referring to the drawings by numerals, 1 designates the lever, which comprises a body 2 and a handle 3. The body 2 is provided with an elongated slot 4 and a plurality of 45 notches 5; the outer end 6, of the body 2, extends at an angle to the longitudinal axis of the main portion of the body, and pivotally mounted on bolt or rivet 7 is an auxiliary jaw device 8. Pivotally mounted on 50 bolt 9 is a primary jaw device 10; bolt 9 may be seated in either one of the notches 5, for the purpose hereinafter specified.

55 The primary jaw device 10 comprises plates 11; these plates 11 are spaced apart by sleeve 12 on rivet 13, Fig. 5; the bolt 9 also assists in holding plates 11 together,

with the body 2 therebetween. On the outer ends of plates 11 are formed right-angularly positioned jaws 14; each jaw 14 is provided, on its inner face, with integral, inwardly and downwardly-extending spurs or teeth 15. A cable 16 is fastened between the plates 11 to the sleeve 12, and by means of cable 16, the device is suspended in position to be readily accessible for operating upon the grain car 60 door, at the will of the operator; this cable forms a part of the carrier apparatus, described in my co-pending application Serial No. 476,660.

The auxiliary jaw device 8 comprises a 70 hollow body 17 (Fig. 6) having a substantially V-shaped opening 18 in its center, into which opening extends the outer end 6 of the lever, and through which opening, as well as outer end 6 of the lever, extends the 75 bolt or rivet 7. Outwardly and upwardly-extending spurs or teeth 19 are formed upon the ends of the body 17, for engaging and penetrating a wood board 20 (Fig. 2).

The operation of the device is as follows: 80 The device is supported by cable 16 in an accessible position for the operator to quickly swing the device so as to place either one of jaws 14 inside of the car against the door frame 21; the teeth 15 will be forced into the 85 door frame 21, as soon as downward pressure is brought to bear upon the handle 3 of the lever 1, and as the downward movement increases, the bolt 9 can be moved up to the next notch 5, so as to always gain the 90 greatest amount of leverage, which will result in forcing the board 20 away from the door frame 21 and upward at the same time, as shown by dotted lines 20^a so that each successive board is removed from the framework of the car and forced upwardly above the grain that is stored in the car, allowing the grain to fall out of the car-door and be discharged into a suitable receptacle 95 provided for this purpose, whether it be a chute, or conveyor, or the like (not shown).

Heretofore, in order to remove the doors, or the like, it has been necessary to chop or saw the same, which requires about thirty minutes' time, whereas, they are removed 105 by my device in about three and one-half minutes; a saving of more than twenty-five minutes to each car.

To saw or chop the boards or doors out of the car requires an ax or saw. The operator must climb into the car, for if he stands in front of the door, as it is cut out, he

is in danger of being injured by the boards as they are forced out by the grain. This may occur as well if he stands up in the car and the boards give way under the saw or 5 ax, whereas, by the use of my device, the operator stands six or more feet away from the car door, clear of the grain as it escapes, and there is no possible chance to be injured.

When the boards are sawed or chopped 10 out, they are necessarily destroyed and cannot be used again, whereas, by the use of my device, they are simply lifted up and left intact and may be used again. Quite a saving results from the use of my device.

15 While I have described the preferred embodiment of my invention, and have illustrated the same in the accompanying drawings, certain minor changes or alterations may appear to one skilled in the art to 20 which this invention relates, during the extensive manufacture of the same and I, therefore, reserve the right to make such alterations or changes as shall fairly fall within the scope of the appended claims.

25 What I claim is:

1. In a device of the class described, the combination of a lever, a jaw device straddling said lever, said jaw device provided with oppositely-extending jaws, teeth on 30 said jaws, and a second jaw device carried by said lever.

2. In a device of the class described, the combination of a lever, a primary jaw device straddling said lever, means fastening said jaw device to said lever, said jaw device provided with oppositely-extending jaws, wood-penetrating means formed on the inner faces of said jaws, and an auxiliary jaw device carried by said lever. 35

3. In a device of the class described, the 40 combination of a lever, a primary jaw device carried by said lever comprising a pair of plates, a sleeve between said plates, a rivet in said sleeve and plates, said plates provided at their outer ends with integral, 45 right-angularly-disposed jaws, said jaws provided on their inner faces with integral, inwardly and downwardly extending spurs or teeth, and an auxiliary jaw device carried by said lever. 50

4. In a device of the class described, the combination of a lever, a primary jaw device pivotally and adjustably mounted on said lever, said jaw device provided with oppositely extending jaws, said jaws provided on their inner faces with wood-penetrating means, and an auxiliary jaw device on the outer end of said lever. 55

In testimony whereof I hereunto affix my signature.

IRA B. WHITE.
